UNITED STATES PATENT OFFICE.

JOSEPH R. SHEFFER, OF CHICAGO, ILLINOIS.

UNION SUIT.

1,138,899

Specification of Letters Patent. Patented May 11, 1915.

Application filed March 9, 1914. Serial No. 823,481.

To all whom it may concern:

Be it known that I, JOSEPH R. SHEFFER, citizen of the United States, residing at Chicago, in the county of Cook and State of Illinois, have invented certain new and useful Improvements in Union Suits; and I do hereby declare the following to be a full, clear, and exact description of the invention, such as will enable others skilled in the art to which it appertains to make and use the same.

My invention relates to combination undergarments or so-called union suits and more particularly to garments of this class cut from knitted materials and suitable for men's and children's wear.

Among the objects of my invention are that of providing a combination garment which may be quickly and cheaply constructed of relatively few pieces; which will require only a single and conveniently located button for fastening the drop flap; which will afford a maximum of only two thicknesses of fabric at the seat; and in which the rear of the body portion will contact with the flap in affording the required opening when the flap is lowered.

Other objects are to provide a flap construction which will normally afford expansibility in a substantially horizontal direction at the waist and in a substantially vertical direction at the crotch, and which will afford expansibility in a direction diagonal to the horizontal when the flap is lowered.

A further object is to provide a flap in which the desired elasticity and expansibility may be obtained in two or more of the said directions by a suitable disposition of the wales of the fabric.

Still another object is to provide a union suit equipped with a flap detachable from the body of the garment at only one of its lateral edges and folding back along a line reaching substantially from one upper corner of the flap to a point adjacent to the hip joint of the wearer at the opposite edge of the flap.

In the drawings, Figure 1 is a rear view of an under garment embodying my invention. Fig. 2 is a view of the flap portion of the same. Fig. 3 shows the component parts of the flap of Fig. 2. Fig. 4 is a fragmentary view of the pattern for the body portion of the union suit of Fig. 1. Fig. 5 shows an alternative form of flap.

In the embodiment of the drawings, the

combination undergarment of my invention consists essentially of two portions, namely a body member 1, which may be equipped with sleeves 2 of any suitable length, and a substantially hexagonal flap member 3 secured along four of its sides to the said body member. In manufacturing the main member of such a garment from tubular knit goods, the vertical opening for the front of the garment is cut after the usual fashion, and substantially triangular or wedge-shaped pieces are cut out of the tubular fabric intermediate of the said front opening, so as to afford a substantially keystone-shaped opening 5 as shown in Fig. 5. The said opening 5 is preferably slightly narrower in extreme width than the substantially hexagonal flap 3, which flap preferably has its lower end arched or curved as shown in Fig. 2. When the flap member is secured to the body member of the garment, as shown in Fig. 1, by lines of stitching following the edges 6, 7, 8 and 9 of the said flap member, the edges 7 and 9 extending over thigh portions of the legs coact with the curvature of the lower edge 8 to enable this edge to follow the upper inside portions of the legs of the garments substantially to the crotch. The upper edge 10 of the flap member is preferably disposed along the waist line of the garment and equipped at the upper corner adjacent to its loose side 12 with a button-hole 11 whereby it may be fastened to a button 13 secured to the body member of the garment near the waist line thereof. It will be evident from Figs. 1 and 2, that by thus disposing the lower edge 8 of the hexagonal flap member substantially along the inner edges of the leg members of the garment, the adjacent edges 7 and 9 of the substantially hexagonal flap member will be drawn toward each other, thereby affording the desired fullness at the seat portion of the garment. It will also be evident that by loosening the free upper corner of the flap member at the button 13, the adjacent corner portion of the flap may be dropped back as shown in dotted lines in Fig. 1, so as to afford an opening at the back of the garment. To make this opening more effective, the back of the body portion of the garment which depends within the said flap is preferably cut away diagonally as shown at 14 in Fig. 1, or along a line substantially parallel to the diagonal line 15 about which the said flap is folded when

dropped. By thus diagonally shortening the depending inner portion of the body member at the side opposite the open edge 12 of the flap, I am able to produce a larger effective opening when the flap is lowered, while still affording an effective closure when the flap is in its normal position and am also able to provide the maximum posterior opening at the point where it is most needed, viz. a point above the crotch and substantially in horizontal alinement with the hip joint of the wearer.

In order to afford real comfort to the wearer, it is desirable to provide elasticity and expansibility in three different directions at different portions of the flap member of a garment of this class. Thus, at the upper edge of the flap (or substantially the waist line of the garment), it is desirable to have expansibility in a horizontal direction so that the upper edge of the flap will expand simultaneously with the adjacent portions of the back of the body member in adjusting themselves to the contour of the wearer. On the other hand, the strains upon the garment when the wearer seats himself tend to extend the lower or crotch portion of the flap member in a direction at right angles to that just described, that is to say, substantially vertical of the flap member. Then, when the flap is lowered, the stretching required for readily affording the desired opening will demand an expansion substantially along the line 15, or at a diagonal with the horizontal along a line extending from one upper corner of the flap member to a point at the other side of the flap in proximity to the hip joint of the wearer of the garment. I preferably provide for the desired expansion and elasticity in the said three directions by making the flap member 3 of two portions adjoined substantially along the central vertical line of the said flap member, the edges 17 thus adjoined being curved in the pattern from which they are cut, as shown in Fig. 3, and the wales of the fabric forming the said portions being so disposed that the said wales will be substantially continuous and horizontal at the crotch portion of the said composite flap. It will be evident from the drawings that the curvature of the said adjoined edges will readily enable the flap to conform better to the curvature of the portion of the figure covered by the flap, and that the said disposition of the wales of the fabric in the substantially arcuate members comprising the flap will cause the wale to be approximately vertical at the upper edges of the flap, and diagonal at points intermediate between the said upper edge and the crotch portion of the flap member. Consequently, I am enabled to provide the desired elasticity in all three of the aforesaid directions without introducing a composite weave

into the flap member. Moreover, the pointing of the adjoined lower tips of the flap portions will cooperate with the concavity of the adjoined edges of the said portions to enable the said tips to be brought past the crotch and part way up the front of the garment in assembling the latter, thereby avoiding the unpleasant rigidity of a seam at the crotch and also permitting expansibility along a line reaching from the upper permanently secured corner of the flap down

through the crotch and part way up the front of the garment. However, I do not wish to be limited to this particular means of providing the required expansibility, as the same might be varied by equipping the upper end of the flap member with a weave 16 having wales in a vertical direction, the said portion 16 being woven with an elastic ribbing. Likewise, the desired elasticity may be secured in a vertical direction at the crotch portion of the flap by making this portion of a gusset 18 in which the wales run horizontally, or substantially at right angles to the wales of the upper portions of the flap, as shown in Fig. 4. Besides enabling the tips of the adjoined flap portions to be secured to the front of the garment considerably above the crotch thereof, the concavity of the adjoined edges of the said portions also causes the juncture thereof to be thrown forwardly of the garment, thereby enabling the said flap portions to afford a convexity conforming to the portions of the body covered thereby. The rear of the garment therefore fits the body snugly, while the avoiding of all slots or lateral openings in the leg portions of the garment prevents the gapping common in the union suits heretofore in use, or the corresponding discomfort of the flaps needed for covering such slitted leg portions.

While I have shown and described the body portion of my union suit as cut from tubular knit fabric, it will be evident that the same could be fashioned in the knitting. It will also be evident that the various details of the construction herein shown and described may be varied in many ways without departing from the spirit of my invention, hence I do not wish to be limited to the precise embodiment herein disclosed.

I claim as my invention:

1. A union suit comprising a main member having a posterior opening extending through the crotch portion and into opposed parts of the leg portions; and a flap member normally closing said opening up to a line reaching from below the belt line at one side of the back of the wearer of the garment to a point proximate to the hip joint at the other side thereof, the back of the main member terminating below and substantially parallel to said line and the elasticity of the flap member so disposed as to

afford a maximum expansibility substantially along said line.

2. In a garment of woven material having a posterior opening, a flap for closing said opening, the said flap integral with the crotch portion of the garment and permanently fastened along the whole of one of its lateral edges and along the other lateral edge up to a point above the crotch, the said flap presenting a side opening extending from the said point to the upper end of the last named lateral edge and detachably secured to the garment at its said upper end of said edge: the weave of the said flap providing a maximum expansibility substantially along a line reaching from the said point on one lateral edge of the flap to the upper end of the said permanently fastened lateral edge, thereby enabling said flap to stretch along said line to afford the required posterior opening when the flap is folded back along the said line.

3. A combination undergarment comprising a main body-and-leg member provided with a posterior opening extending through the crotch and downwardly into opposing parts of the leg portions thereof, and a flap member extending from the front of the garment through the crotch and over the back portion thereof and comprising two equal parts joined together by a seam extending midway through the crotch and up the middle of the back, the wales of said flap member diverging from said seam at angles gradually increasing from the upper end portion of said flap member at the back of the garment through said crotch, whereby the said disposition of the wales renders said flap member most elastic to strains acting in a direction substantially transverse to said seam at the upper portion of said flap and substantially parallel with said seam in the crotch portion of the flap member.

4. A combination undergarment comprising a main member equipped with a posterior opening, and a flap member secured to the garment and normally closing the said opening, the said flap member comprising

ing a pair of substantially arcuate portions secured to each other along their concave edges, the juncture of the said portions disposed substantially vertically of the garment, the concavity of the said adjoined edges causing the said juncture to be drawn forwardly of the garment when the latter is in use.

5. A combination undergarment comprising a main member equipped with a posterior opening, and a flap member secured to the garment and normally closing the said opening, the said flap member comprising a pair of substantially arcuate portions secured to each other along their concave edges, the juncture of the said portions disposed substantially vertically of the garment, the concavity of the said adjoined edges causing the said juncture to be drawn forwardly of the garment when the latter is in use, the said arcuate portions equipped at the lower end of their said concave edges with relatively pointed tips, the said tips extending through the crotch and up the front of the garment.

6. A combination undergarment comprising a main member equipped with a posterior opening, and a flap member secured to the garment and normally closing the said opening, the said flap member comprising a pair of laterally adjoined portions having the wales thereof extending at divergent angles from the juncture thereof, the said portions equipped at the lower end of their juncture with relatively pointed tips extending through the crotch and up the front of the garment, the said disposition of the wales affording a maximum of extensibility of the flap along a line reaching from one of the said tips to an extreme upper corner of the flap member.

In testimony whereof I have signed my name in presence of two subscribing witnesses.

JOSEPH R. SHEFFER.
